HAND MACHINE FOR WASHING CLOTHES

Patrizia Quirico, New York, N. Y.

Application August 11, 1937, Serial No. 158,461

9 Claims. (Cl. 68—19)

This invention relates to new and useful improvements in a hand machine for washing clothes.

The invention has for an object the construction of a device as mentioned which is characterized by the fact that it has an element adapted to engage clothes in a tub or the like, and adapted to move in various positions so as to assist in washing the clothes.

More specifically, it is proposed to support the element in a particular fashion so that it may assume universal positions and in each of the various positions it is possible to properly manipulate the cleansing element.

It is proposed to arrange a manipulating handle in conjunction with the cleansing element in a particular fashion.

Still further the invention contemplates an arrangement whereby the support means for the cleansing element is arranged in a manner so that it is locked in pre-selected positions upon depression of the handle controlling the element.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a perspective view of a device constructed according to this invention.

Fig. 2 is a plan view of Fig. 1, the broken support wall being shown in section.

Fig. 3 is a fragmentary sectional view taken on the line 3—3 of Fig. 2.

Fig. 4 is a fragmentary enlarged sectional view taken on the line 4—4 of Fig. 2.

Fig. 5 is a transverse sectional view taken on the line 5—5 of Fig. 4.

Fig. 6 is a fragmentary sectional view taken on the line 6—6 of Fig. 3.

Fig. 7 is a fragmentary horizontal sectional view taken on the line 7—7 of Fig. 6.

Fig. 8 is a plan view of a tub with a modified form of hand machine for washing clothes mounted thereon.

Fig. 9 is a fragmentary sectional view taken on the line 9—9 of Fig. 8.

Fig. 10 is a fragmentary horizontal sectional view taken on the line 10—10 of Fig. 9.

Fig. 11 is a perspective view of a portion of Fig. 9.

Fig. 12 is a sectional view similar to Fig. 3

but illustrating a modification of the invention.

Fig. 13 is a fragmentary sectional view taken on the line 13—13 of Fig. 12.

Fig. 14 is a transverse sectional view taken on the line 14—14 of Fig. 12.

The hand machine for washing clothes, according to this invention, includes a bracket 10 for attachment on a wall or object 11 and an arm 12 swivelly mounted horizontally on the bracket 10. A member 13 is slidably mounted on the arm 12 to be longitudinally extendable thereto. A cleansing element 14 for engaging the clothes in a tub or the like is vertically and slidably mounted on the member 13. Resilient means 15 is provided for urging the said element 14 upwards. A handle 16 is connected with the top end of the element 14 intermediate of its ends and its rear end is flexibly connected with the inner end of the member 13.

The bracket 10 comprises a board or plate 20 which is attached to the wall of object 11. The swivel mounting of the arm 12 is accomplished in the following manner. The inner end of the arm 12 has a vertically disposed inner end portion 12^a, 12^b, the ends of which are engaged by 25 a pair of horizontally disposed straps 17. These straps act as bearings for holding the ends 12^a and 12^b in a manner so that the arm 12 may swivel horizontally of the bracket. The member 13 is in the form of a tube telescopically engaged on the arm 12. These parts are square or rectangular in transverse cross section so as to prevent relative turning of the parts while permitting the slidable extension and retraction.

The cleansing element 14 comprises a rubber 35 or similar cup shaped element 14^a secured upon the bottom end of a vertical rod 14^b which is slidable through the outer end of the member 13. The upper end of the rod 14^b is provided with a fork-shaped bearing element 14^c. The 40 outer end of the rod 13 is formed with a recess 19 into which the bottom end of the spring 15 engages. The spring 15 is arranged coaxial of the rod 14^b and acts to normally urge the cleansing element 14 upwards into a raised position.

The handle 16 passes between the arms of the fork 14^c and is pivotally held connected thereto by a pintle 20. The inner end of the handle is pivotally connected with a link 21, which in turn 50 is pivotally connected with a fork shaped bracket 22 mounted on the rear end of the member 13.

The operation of the device is as follows:—

An operator holds the outer end of the handle 55. By this handle he is capable of pivoting

the device to the right or left as indicated by the dot and dash lines in Fig. 2. In all horizontally pivoted positions the operator is capable of moving the member 13 inwards or outwards to various 5 extended positions also indicated by dot and dash lines in Fig. 2. The device is operated merely by reciprocating the handle 16 upwards and downwards which forces the cleansing member 14 correspondingly to engage against clothes in a tub 10 24 or other receptacle for holding water, cleansing agents, and the clothes to be washed.

In Figs. 8-11 inclusive another embodiment of the invention has been disclosed which distinguishes from the prior form merely in the bracket 15 for supporting the arm 12. According to this form of the invention there is a transverse support bar 25 having a rectangular shaped flat portion 25^a at its center. At its ends it is provided with vertical rod portions 25^b. These rod portions are adapted 20 to slidably engage a pair of spaced clamps 26 which are attached upon support elements 27 adapted to be mounted over the top edge portions of the tub 24. The clamps 26 are provided with screws 28 by which they may be manipulated to 25 hold the bar 25 in raised or lowered positions. The supporting members 27 are adapted to hold the bar 25 transversely of the tub, as clearly shown in Figs. 8 and 9. The inner end of the arm 12 is swivelly mounted horizontally in the 30 frame portion 25^a. In other respects this form of the invention is similar to the previous form and similar parts may be identified by corresponding reference numerals.

In Figs. 12 to 14 inclusive another embodiment 35 of the invention has been disclosed in which a means is provided for holding the arm 12^{ab} against swivelling when pressure is applied on the handle 16. This means consists in the provision of a bolt 22^a connected at its top end with the 40 fork member 22'. This bolt 22^a extends through a slot 30 formed in the arm 12^{ab}. The bolt 22^a has a head 22^{aa} the inner face of which is serrated. This bolt engages through an opening 31 formed in the bottom portion of the member 13. 45 The bolt 22^a is normally loose so that when the handle 16 is gripped and pulled forwards or pushed rearwards the member 13 will merely slide on the arm 12^{ab}. But as soon as the handle 16 is forced downwards the inner end of the handle 50 will be forced upwards, and the bolt 22^a will be forced upwards so that its head 22^{aa} engages against the material on the bottom face of the arm 12^{ab} and so holds the member 13 and the arm 12^{ab} fixedly connected together.

In the form of the invention shown in Figs. 55 12-14 inclusive, there is a means for holding the arm 12^{ab} from swivelling when pressure is applied to the handle 16. This means includes an upper bearing 33 and a lower bearing 34 for vertically slidably supporting the head portion 12^{aa} and 12^{bb} of the arm 12^{ab}. The bearing 33 is fixedly held by the upper strap 17, while the bearing 34 is pivotally held by the lower strap 17. The upper end of the head 12^{aa} slidably engages into 60 the bearing 33 and is normally urged upwards by a coaxially mounted spring 36 acting between a portion of the part 12^{aa} and a part of the bearing 33.

The lower portion 12^{bb} of the arm 12^{ab} is provided 70 with a flanged portion 37 having serrations 38 upon its bottom face adapted to engage against the top edge of the bearing 34 for frictionally holding these parts together. When the handle 16 is pressed downwards the spring 36 will be 75 compressed and the arm 12^{ab} will move down-

wards so that the serrations 38 engage the bearing 34 and hold the arm 12^{ab} against swivelling. It is only possible to swivel the arm 12^{ab} when the handle 16 is free. Then the handle may be gripped and moved to the right or left.

An important feature of the invention resides in the fact that the handle 16 of each of the various forms is flexibly connected at its rear end with the member 13. Therefore, in all positions 10 of the member 13 relative to the supporting arms and brackets there will be the same mechanical relationship between the handle 16 and the cleansing element 14.

While I have illustrated and described the preferred embodiments of my invention, it is to be 15 understood that I do not limit myself to the precise constructions herein disclosed and the right is reserved to all changes and modifications coming within the scope of the invention as defined in the appended claims.

Having thus described my invention, what I 20 claim as new, and desire to secure by United States Letters Patent is:—

1. A hand machine for washing clothes and the like, comprising a bracket for attachment on a 25 wall or object, an arm swivelly mounted horizontally of said bracket, a member slidably mounted in said arm to be longitudinally extendible thereto, a cleansing element for engaging the clothes in a tub or the like and vertically slidably mounted on said member, resilient means urging said element upwards, a handle connected with the top end of said element intermediate of its ends and having its rear end flexibly connected with the inner end of said member.

2. A hand machine for washing clothes and the like, comprising a bracket for attachment on a wall or object, an arm swivelly mounted horizontally of said bracket, a member slidably mounted in said arm to be longitudinally extendible thereto, a cleansing element for engaging the clothes in a tub or the like and vertically slidably mounted on said member, resilient means urging said element upwards, a handle connected with the top end of said element intermediate of its ends and having its rear end flexibly connected with the inner end of said member, the inner end of said arm being formed with a head portion having oppositely directed elements, and said bracket serving to pivotally support said oppositely directed elements for swivelly supporting the arm as specified.

3. A hand machine for washing clothes and the like comprising a bracket for attachment on a wall or object, an arm swivelly mounted horizontally of said bracket, a member slidably mounted in said arm to be longitudinally extendible thereto, a cleansing element for engaging the clothes in a tub or the like, and vertically slidably mounted on said member, resilient means urging said element upwards, a handle connected with the top end of said element intermediate of its ends and having its rear end flexibly connected with the inner end of said member, said member comprising a tubular element engaged on said arm, and said arm and said member being of shapes to prohibit turning of these parts.

4. A hand machine for washing clothes and the like, comprising a bracket for attachment on a wall or object, an arm swivelly mounted horizontally of said bracket, a member slidably mounted in said arm to be longitudinally extendible thereto, a cleansing element for engaging the clothes in a tub or the like and vertically slidably mounted on said member, resilient means urging 70 said element upwards, a handle connected with the top end of said element intermediate of its ends and having its rear end flexibly connected with the inner end of said member, said member comprising a tubular element engaged 75 on said arm, and said arm and said member being of shapes to prohibit turning of these parts.

said element upwards, a handle connected with the top end of said element intermediate of its ends and having its rear end flexibly connected with the inner end of said member, said resilient means comprising a spring acting between a recess portion in the outer end of said member, and a portion of said cleansing element.

5. A hand machine for washing clothes and the like, comprising a bracket for attachment on a wall or object, an arm swivelly mounted horizontally of said bracket, a member slidably mounted in said arm to be longitudinally extendible thereto, a cleansing element for engaging the clothes in a tub or the like and vertically 10 slidably mounted on said member, resilient means urging said element upwards, a handle connected with the top end of said element intermediate of its ends, having its rear end flexibly connected with the inner end of said member, and means for holding said arm against said 15 swivelling when pressure is applied to said handle.

6. A hand machine for washing clothes and the like, comprising a bracket for attachment on a wall or object, an arm swivelly mounted horizontally of said bracket, a member slidably mounted in said arm to be longitudinally extendible thereto, a cleansing element for engaging the clothes in a tub or the like and vertically 20 slidably mounted on said member, resilient means urging said element upwards, a handle connected with the top end of said element intermediate of its ends, having its rear end flexibly connected with the inner end of said member, and means for holding said member from sliding when pressure is applied to said handle.

7. A hand machine for washing clothes and the like, comprising a bracket for attachment on a wall or object, an arm swivelly mounted horizontally of said bracket, a member slidably mounted in said arm to be longitudinally extendible thereto, a cleansing element for engaging the clothes in a tub or the like and vertically 25 slidably mounted on said member, resilient means urging said element upwards, a handle connected with the top end of said element intermediate of its ends, having its rear end flexibly connected with the inner end of said member, and means for holding said member from sliding when pressure is applied to said handle.

and means for holding said arm against said swivelling when pressure is applied to said handle, comprising a resilient element holding the swivelled arm in a raised position and adapted to be readily compressed when pressure is applied to the handle, and elements upon the arm and a stationary part for holding the arm from swivelling when said element is compressed.

5

8. A hand machine for washing clothes and the like, comprising a bracket for attachment on a wall or object, an arm swivelly mounted horizontally of said bracket, a member slidably mounted in said arm to be longitudinally extendible thereto, a cleansing element for engaging the clothes in a tub or the like and vertically 15 slidably mounted on said member, resilient means urging said element upwards, a handle connected with the top end of said element intermediate of its ends, having its rear end flexibly connected with the inner end of said member, and means for holding said member from sliding when pressure is applied to said handle, comprising a bolt connected with the inner end of said handle and engaging through a longitudinal slot formed in said arm and adapted to 20 engage against the material of the arm when the handle is forced downwards to positively hold these parts together.

25

9. A hand machine for washing clothes and the like, comprising a bracket for attachment on a wall or object, an arm swivelly mounted horizontally of said bracket, a member slidably mounted in said arm to be longitudinally extendible thereto, a cleansing element for engaging the clothes in a tub or the like and vertically 30 slidably mounted on said member, resilient means urging said element upwards, a handle connected with the top end of said element intermediate of its ends and having its rear end flexibly connected with the inner end of said member, said bracket comprising a bar with a flat portion at its center, said arm being swivelly mounted upon said flat portion, and clamps for engaging the ends of said bar and adapted to support said bar on diametrically opposite edges 35 40 45 or a tub or the like.

PATRIZIA QUIRICO.
